UNITED STATES PATENT OFFICE.

EDWARD CROSBY LASHER, OF GRIFFIN CORNERS, NEW YORK.

RAILROAD-TIE.

1,122,132.

Specification of Letters Patent. Patented Dec. 22, 1914.

Application filed May 20, 1914. Serial No. 839,829.

To all whom it may concern:

Be it known that I, EDWARD CROSBY LASHER, a citizen of the United States, residing at Griffin Corners, in the county of Delaware and State of New York, have invented certain new and useful Improvements in Railroad-Ties, of which the following is a specification, reference being had to the accompanying drawings.

10 This invention relates to certain improvements in railroad ties and has relation more particularly to a device of this general character wherein the major portion thereof is produced of metal; and an object of the invention is to provide a device of this general character having novel and improved means whereby a sufficient degree of resiliency is possessed by the tie in order to permit the requisite yield as the rolling stock 20 passes thereover.

Furthermore, my invention has for its object to provide a device of this general character having novel and improved means whereby fastening means for the rails may 25 be engaged therewith in such a manner as to effectively hold such rails against displacement.

The invention consists in the details of construction and in the combination and arrangement of the several parts of my improved railroad tie whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view, partly in side elevation and partly in section, of a tie constructed in accordance with an embodiment of my invention; Fig. 2 is a fragmentary view in bottom plan of the device as herein embodied; Fig. 3 is a view in top plan of a tie constructed in accordance with my invention; Fig. 4 is a sectional view taken substantially on the line 4—4 of Fig. 3; and

Fig. 5 is a sectional view taken substantially on the line 5—5 of Fig. 4.

As disclosed in the accompanying drawings, 1 denotes the base plate of my improved tie, as herein embodied, of predetermined dimensions and having produced on its under face, the elongated lugs or extensions 2 which may be disposed in such directions as will best suit the necessities of 55 practice so that the tie, when rested upon the road bed, is effectively maintained against endwise or lateral movements. This arrangement I have found in practice to be especially advantageous as I find in use that 60 it is best that the tie proper be not embedded or even partially embedded in order that the life of the tie may be prolonged, for reasons which are believed to be self-evident. In 65 view of the fact that I do not wish at this time to make any particular claim to the exact arrangement of the elongated lugs or projections 2, it is not thought necessary that a detailed description thereof need be 70 given, other than to say that I find it especially desirable to have such lugs or projections 75 rectangular in cross section.

Integrally connected with the opposite extremities of the base plate 1 are the substantially L-shape end plates 3, the stems 4 thereof being inwardly directed and overlying the base plate 1 in substantial parallelism, and the inner edges of such stems 4 are adapted to serve as outer side walls for the transverse seats 5 in the completed tie 80 in which the bases of the rails 6 are adapted to be received, as is believed to be self-evident. The superposed portions 4 are also adapted to overlie the top plate 7 and, if desired, such overlying portions 4 may be 85 produced separate from the top member 7.

In order that an increased engaging surface may be possessed by the tie, I find it best to have the base member 1 of a width in excess of the major portion of the tie and to have the longitudinal marginal portions of such base plate turned upwardly, as indicated at 8, in order to afford an effective medium to reduce to a minimum the possibility of dirt or other foreign substances from interfering with the efficiency of the tie, as 95 will be hereinafter fully appreciated. The 100

opposite ends of the laterally projecting portions of the base member 1 are open so as to permit the ready discharge of any water that might be collected thereon, as is believed to be apparent.

From the foregoing description, it will be readily perceived that the base member 1 together with the end members 3 and top member 7 afford an inclosing frame, in which is adapted to be inserted the superposed plates 9 maintained in relative spaced relation through the medium of the transverse blocks 10 carried by the upper surfaces of such plates 9, the blocks 10 on the uppermost plate serving to maintain the springs spaced from the top member 7. Substantially the entire length of the bottom plate 9 is spaced from the base member 1 and, as herein disclosed, this position is maintained by the transverse blocks 10 carried by the under face of the lowermost plate 9 adjacent the extremities thereof, as is believed to be clearly shown in the accompanying drawings. By this arrangement, it is thought to be clearly obvious that as rolling stock passes over the ties, the requisite yield or compression is possessed by the tie as will assure proper riding thereof.

In order to maintain the plates 9 against displacement, I direct through the base member 1, the top member 7 and the overlying portions 4 of the end members 3, the upwardly disposed clamping members 11, herein disclosed as conventional bolts with their coacting burs or nuts, a further detail of which being, it is thought, unnecessary. The intermediate portion of the top member 7 is provided with the auxiliary plate 12 which may be integrally produced therewith, and which serves to complete the formation of the transverse grooves 5, hereinbefore referred to, to receive the rails 6. In order that the rails may be effectively maintained in operative position, I find it of advantage to have upwardly disposed through the top plate 7, the clamping bolts 14 adapted to coact with the clamps 15, herein disclosed as in engagement with the inner flanges of the rails 6, while the outer flanges of the rails are engaged by the clamps 16 with which coact the upwardly disposed bolts 17 also directed through the top member 7 and through the overlying portions 4 and coacting with such clamps 16 are the binding members 18 provided intermediate their length with the inwardly disposed open-ended slots 19 adapted to accommodate the clamping bolts 17, while the opposite extremities thereof are provided with the substantially L-shape depending members 20 adapted to interlock with the marginal portions of the top member 7, as is believed to be clearly shown in the accom-

panying drawings, and, in order that this interlocking engagement may be effected with convenience and facility, it is to be observed that the top member 7 is of a width in excess of the width of the spring plates 9.

From the foregoing description, it is thought to be obvious that a railroad tie 70 constructed in accordance with my invention is of an extremely simple and comparatively inexpensive nature and is particularly well adapted for use by reason of the convenience and facility with which 75 it may be assembled, and it will also be obvious that my invention is susceptible of some change and modification without material departure from the principles and spirit thereof and for this reason I do not 80 wish to be understood as limiting myself to the precise arrangement and formation of the several parts herein shown in carrying out my invention in practice.

I claim:

1. A railroad tie comprising an inclosing frame, superposed spring plates positioned within said frame, means interposed between adjacent plates for maintaining the same normally in spaced relation, and means 90 directed through the frame and the spring plates for holding the plates against displacement.

2. A railroad tie comprising an inclosing frame, superposed spring plates positioned within said frame, and means directed 95 through the frame and the spring plates for holding the plates against displacement, the base of the frame being of a width in excess of the upper portions of the tie. 100

3. A railroad tie comprising an inclosing frame, superposed spring plates positioned within said frame, and means directed through the frame and the spring plates for holding the plates against displacement, the base of the frame being of a width in 105 excess of the upper portions of the tie, the longitudinal marginal portions of the base being turned upwardly.

4. A railroad tie comprising an inclosing frame, superposed spring plates positioned within said frame, and means interposed between adjacent plates for maintaining the same normally in spaced relation, means for holding the plates against displacement, and rail engaging means operatively engaged with the top of the frame. 110

5. A railroad tie comprising an inclosing frame, superposed spring plates positioned within the frame, blocks interposed between adjacent plates at intervals for maintaining the plate normally in spaced relation, and means for holding the plates against displacement. 120

6. A railroad tie comprising an inclosing frame, superposed spring plates positioned 125

within said frame, and means directed through the frame and the spring plates for holding the plates against displacement, said spring plates being normally maintained in spaced relation.

5 7. A railroad tie comprising an inclosing frame, superposed spring plates positioned within said frame, said spring plates being normally maintained in spaced relation, and

means for maintaining the spring plates 10 against displacement.

In testimony whereof I hereunto affix my signature in the presence of two witnesses.

EDWARD CROSBY LASHER.
